United States Patent Office

Des. 214,415
Patented June 10, 1969

214,415

KNIFE

Homer S. Lynn, 3379 Martin Road, Dublin, Ohio 43017, and Clifford W. Lynn, Bennington Township, Licking
County, Ohio (Rte. 2, Centerburg, Ohio 43011)

Filed Apr. 18, 1968, Ser. No. 11,503

Term of patent 14 years

Int. Cl. D7—03

U.S. Cl. D95—3

FIG 2

I claim:

The ornamental design for a knife, substantially as shown and described.
